(57) **CLAIM**

The ornamental design for a dice, as shown and described.

DESCRIPTION

FIG. 1 is a front perspective view of a dice showing our new design according to a first embodiment of the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a dice showing our new design according to a second embodiment of the present invention;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a front perspective view of a dice showing our new design according to a third embodiment of the present invention;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof;

FIG. 21 is a bottom plan view thereof;

FIG. 22 is a front perspective view of a dice showing our new design according to a fourth embodiment of the present invention;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top plan view thereof;

FIG. 28 is a bottom plan view thereof;

FIG. 29 is a front perspective view of a dice showing our new design according to a fifth embodiment of the present invention;

FIG. 30 is a front elevation view thereof;

FIG. 31 is a rear elevation view thereof;

FIG. 32 is a left side elevation view thereof;

FIG. 33 is a right side elevation view thereof;

FIG. 34 is a top plan view thereof;

FIG. 35 is a bottom plan view thereof;

FIG. 36 is a front perspective view of a dice showing our new design according to a sixth embodiment of the present invention;

FIG. 37 is a front elevation view thereof;

FIG. 38 is a rear elevation view thereof;

FIG. 39 is a left side elevation view thereof;

FIG. 40 is a right side elevation view thereof;

(Continued)

FIG. 41 is a top plan view thereof; and,
FIG. 42 is a bottom plan view thereof.
